CLAIM

The ornamental design for an applicator, as shown and described.

DESCRIPTION

FIG. 1 is a top, front perspective view of embodiment one, of an applicator, showing my new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is an exploded top view thereof, shown with environmental caps;

FIG. 9 is a top, front perspective view of embodiment two, of an applicator, showing my new design; and,

FIG. 10 is a top view thereof.

The broken lines in the figures illustrate the portions of the design that form no part of the claimed design.

The broken lines caps in FIG. 8 illustrate environmental subject matter that forms no part of the claimed design.

(Continued)

The applicator has been shown with symbolic breaks. The appearance of any portion of the article between the break lines form no part of the claimed design.
